TAPE DECK

Ronald E. Loosen, Woodland Hills, and Leon C. Sanderson, Los Angeles, Calif., assignors to Ampex Corporation, Redwood City, Calif., a corporation of California

Filed Dec. 9, 1965, Ser. No. 195

Term of patent 14 years

(Cl. D26—5)

FIGURE 1 is a left side and front perspective view of a tape deck, showing my new design; and

FIGURE 2 is a broken away side elevational view thereof to an enlarged scale, the opposite side being substantially a mirror image thereof.

The dominant features of my new design are shown in solid lines in the drawing. The conventional cabinet shown in broken lines is for illustrative purposes only.

We claim:

The ornamental design for a tape deck, substantially as shown and described.
